AUTOMATIC CONTROL AND ELECTRIC
IGNITION FOR GAS BURNERS

James Bernard Williams, Minden, La.

Application October 1, 1934, Serial No. 746,477

2 Claims. (CL 158—117.1)

The object of the invention is to provide a control for gas burners, as well as an electric ignition for the same, the two being so coordinated that there may be no chance of the escape at any time of unburned gas in the event of failure of the ignition, or failure of the gas supply and subsequent resumption thereof; to provide an ignition and control equipment of the kind indicated which is susceptible of remote control, either through the gas supply or through the ignition equipment; and generally, to provide an automatic gas burner control and ignition which is of simple form, susceptible of cheap manufacture, of a character that is not practically subject to disarrangement or failure of its parts, and of a form which will permit its installation without the necessity of skill on the part of the person making the installation.

With this object in view, the invention consists of a construction and combination of parts of which a preferred embodiment is illustrated in the accompanying drawing, wherein

The figure is a view partly in diagram and partly in section of an appliance constructed in accordance with the invention.

The burner 10 is not directly ignited from the ignition equipment but from a pilot burner 11 which is ignited by the ignition equipment. The main burner 10 is fed from the gas supply conductor 12 through a gas pressure chamber 14 defined by a diaphragm 15 and certain walls of the casing 16, the latter being formed in two parts consisting of the lower section 16a and the upper section 16a which are bolted together by means of fasteners 18 passed through the flanges 17, with which both sections of the casing are formed. The diaphragm is marginally interposed between the connecting edges of the casing, and at its center is connected with a post 19 passing slidably through a central guide opening in the upper section 16a of the casing and through an opening in the guide arm 20 with which the upper section of the casing is formed. Exterior to the casing, the post carries a lateral arm 21 terminally provided with a contact 22, the latter being insulated from the arm but positioned to engage a complementary contact 23 carried at the extremity of a lever 24, the latter being pivotally mounted on a base plate 25 of insulating material, on which an L-shaped abutment member 26 is also mounted. The contact end of the lever 24 is yieldingly forced downwardly into engagement with the end of the short leg of the abutment member 26, a compression spring 27 being employed for this purpose and

being telescoped over projections at the extremities of the lever and the abutment member. Thus downward movement of the lever carrying contact is limited by the abutment member, but the lever may yield in an upward direction, when the contact 23 is engaged by the contact 22, as will be the case when the post is elevated, due to the pressure of gas in the chamber 14 acting on the underside of the diaphragm 15.

The supply pipe, in which at a remote point 10 from the burner is positioned the control valve 28, is in communication with the gas pressure chamber, but the burner 10 is in communication with said chamber only when the valve 29 is in open position, this valve being interposed between the inlet and outlet of the gas pressure chamber. The valve 29 is formed with a stem 30 which extends through a guide opening in the bottom of the casing section 16a and is terminally provided with a plunger 31, which acts as the core of a solenoid 32, the latter being wound on a bobbin 33 of brass or other non-magnetic material, which is frictionally or otherwise secured to the boss 34, with which the bottom section 16a of the casing is formed. When the solenoid is energized, the core 31 will be elevated and retained in elevated position to hold the valve 29 in open position. When the solenoid is deenergized, the plunger or core 31 will drop to bring the valve 29 to closed position. An interlocking connection 35 is formed between the stem 30 and valve 29 to facilitate the assembling operation. The bobbin 33 is extended below the lower end of the solenoid winding and is closed with a removable cap 36, sufficiently tight fitting to prevent the escape of any gas that might find its way out of the outlet channel of the casing around the hole or guide opening through which the stem 30 passes. Sufficient guide clearance is provided between the plunger and the wall of the bobbin to permit the ready transfer of air from one to the other in the movement of the plunger, so as to prevent sluggish operation of the latter.

The pilot burner 11 is fed through a branch tubular conductor 37 tapped into the main supply pipe 12 between the control valve 28 and the gas pressure chamber 14, the conductor 37 being provided with a manually adjustable valve 38 to regulate the supply of gas to be admitted to the pilot burner. A valve 39 is interposed in the pilot supply pipe or conductor 37, being housed in a valve case 40 and having a stem 41 terminating in a solenoid plunger core 42. The core 42 moves within the bobbin 33, which is also of non-magnetic material, frictionally or otherwise secured 55

to a pendent boss 44 on the bottom of the case 40. The solenoid winding 45 is wound upon the bobbin, the latter at its lower end being closed with a movable gas tight cap 46 of the same form 5 as the cap 36.

The solenoids 32 and 45 which constitute the actuating means for the valves 28 and 39 are actuated from the secondary of a transformer 47, whose primary is fed from the line conductors 48, in series with the switch comprising the contacts 22 and 23. The ignition coil 49 is also fed from the secondary of the transformer 47 in one position of the thermostatically operated single-pole double-throw switch, which comprises the fixed contacts 50 and 51 and the movable contact 52, the fixed contacts being carried on a bracket 53 and the movable contact being carried on a strip of thermo-metal 54, also carried upon the bracket. The thermo-metal and fixed contacts are insulated from the bracket and the fixed contact 51 is electrically connected with one of the primary terminals of the spark or ignition coil 49, the common terminal of which is grounded. The fixed contact 50 is electrically connected with the solenoid 32 so that when the movable contact 52 engages the contact 53 the solenoid 32 will be energized.

The electrode 55, by means of which the pilot burner 11 is ignited, is electrically connected with the secondary terminal of ignition coil 49. The ignition coil is of the vibrator type, which has been found to give the most intense spark.

To provide for remote control through the ignition apparatus, a switch 56 is interposed in the supply line 48.

In the operation of the invention, the burner is absolutely precluded from being ignited if the switch 56 be open or if the valve 28 be closed. The latter must be open and the former closed 40 for the apparatus to operate. If gas be present in the supply pipe 12, it will enter the pressure chamber 14, and exerting the pressure on the diaphragm 15, will bulge the latter upwardly, thereby elevating the post 19 to engage the contact 22 with the contact 23. Then a circuit is 45 established in the primary of the transformer 47 over the supply conductors 48. With the primary of the transformer energized, the secondary will also be energized and the current will flow from 50 it to the solenoid 45, thence to the ground and thence back to the secondary, one terminal of the solenoid winding being grounded, as well as one terminal of the transformer secondary. Energizing of the solenoid 45 will result in the elevation of its core 42 and the opening of the valve 43, so that gas may flow through the conductor 31 to the pilot burner, such gas being ignited 55 by the sparking at the electrode 55, since, when the thermo strip 54 is cool, the contact 52 will be in engagement with the contact 51 and current from the secondary of the transformer may flow from the latter over the engaged contacts to the primary of the ignition coil, thence to the ground and back to the transformer. But upon 60 the pilot burner being lighted, the thermo strip will be heated, with the result that the unequalled expansion of its constituent laminae will result in engaging the contact 52 with the contact 53, thus breaking the circuit on the primary of the 65 ignition coil, and therefore rendering it inert, so that there will be no sparking at its electrode. But the engagement of the contacts 52 and 53 will place the solenoid 32 in circuit with the secondary of the transformer 47, current flowing 70 from said secondary over the engaged contacts

52 and 50, thence through the solenoid winding and the ground back to the secondary. By energizing the solenoid 32, the resultant elevation of the plunger 31 will move the valve 28 to open position, so that gas may flow to the main burner 10 to be ignited by the previously ignited pilot burner.

Should the gas supply fail, the pressure in the pressure chamber 14 will drop and the diaphragm 15 will resume its normal position, separating the contacts 22 and 23, thus depriving the transformer 47 of current, and therefore depriving both the solenoids 32 and 45 of current, so that their cores will drop and their valves be moved to closed position. Thus communication between the supply and both the main and pilot burners will be cut off. On the resumption of the gas supply, the pressure again obtaining in the gas pressure chamber 14, will result in the re-engagement of the contacts 22 and 23, and thus the establishment of former conditions, resulting first in the re-ignition of the pilot burner and thereafter the main burner.

If the switch 56 be open during the failure of the gas supply, or if the ignition circuit be affected, so that the pilot burner cannot be ignited, the gas supply to the main burner cannot be established, since that is wholly dependent on the engagement of the contacts 52 and 50, which can only be maintained when the pilot burner has been ignited.

The valve 39 is not an absolute necessity to the proper functioning of the device, but is only included as an extra precaution against gas escape. It may, therefore, be omitted where the escape 35 of a small amount of gas required for the pilot burner may not constitute a hazard.

The invention having been described, what is claimed as new and useful is:

1. An appliance of the kind indicated comprising, in combination with a gas burner and a gas conduit feeding the same from a gas supply source, a gas pressure chamber interposed in the conduit and continuously exposed to pressure from the source, a valve controlling communication between the pressure chamber and the burner, a pilot burner having a conduit feeding it from the gas supply source from a point ahead of the pressure chamber, a valve interposed in the pilot conduit, an electrical actuating means for the burner valve, an electrical actuating means for said pilot valve, an energizing circuit across which the pilot valve actuating means is connected, electrical ignition apparatus for the pilot burner, a double-throw single-pole thermostatically operated switch normally in one of its circuit closing positions to connect the ignition apparatus in the energizing circuit and heat actuated from the pilot burner to its other circuit closing position to connect the burner valve actuating means in the energizing circuit, and a normally open circuit closer controlling the energizing circuit and operatively related with the gas pressure chamber for movement into closed position on the attainment of a predetermined pressure in the pressure chamber.

2. An appliance of the kind indicated comprising, in combination with a gas burner and a gas conduit feeding the same from a gas supply source, a burner valve interposed in said conduit and controlling the admission of gas to the burner, means for normally retaining said valve in closed position, electrical means for opening said valve, a pilot burner having a conduit feeding it from the gas supply source from a point

ahead of the burner valve, a valve interposed in the pilot conduit, means for normally retaining the pilot valve in closed position, electrical means for opening said pilot valve, ignition apparatus for the pilot burner, means responsive to a predetermined pressure of gas in the first said conduit to admit energizing current to the pilot valve

opening means and to the ignition apparatus, and means responsive to combustion at the pilot burner and operatively connected with the ignition apparatus to de-energize the latter and admit energizing current to the burner valve opening means only after ignition of the pilot burner. 5
